UNITED STATES PATENT OFFICE.

IRVING S. BENJAMIN AND JOHN K. MARKWICK, OF UTICA, NEW YORK; SAID
MARKWICK ASSIGNOR TO SAID BENJAMIN.

FUEL SAVER AND SMOKE CONSUMER.

Application filed February 25, 1924. Serial No. 694,960.

To all whom it may concern:

Be it known that we, IRVING S. BENJAMIN and JOHN K. MARKWICK, citizens of the United States, and residents of Utica, in the county of Oneida and State of New York, have invented certain new and useful Improvements in Fuel Savers and Smoke Consumers; and we do hereby declare that the following is a full, clear, and exact description thereof, which will enable others skilled in the art to which it appertains to make and use the same, reference being had to the accompanying drawings and to the reference numerals marked thereon, which form part of this specification.

Our present invention relates to a fuel saver and smoke consumer of the type adapted to be applied to a furnace or stove door and operating to admit heated air to the combustion chamber of the furnace.

The main object of our invention is to provide a device of the character described, which is simple and strong in construction, readily applied to the ordinary furnace door and well adapted to provide an adequate supply of thoroughly preheated air.

A further object is to provide a device of the character described, where the air is heated not only by being carried through heated chambers in the device; but is also heated by being mixed with a current of hot gas temporarily drawn into the device from the combustion chamber of the furnace.

Another object of our invention is to provide a device where the heater proper is readily adjusted relative to the support or mounting piece upon the furnace door, so that the device may be readily adjusted to different makes and sizes of furnaces and still be efficient in use.

Another purpose of the invention is to provide a preheater of such special arrangement, construction and combination of its parts that a constant and sufficient current of air will be thoroughly heated and so that a current of heated gas will be taken into the device from the combustion chamber and thoroughly mixed with incoming partly heated air and thereafter such mixture will be further heated and then ejected into the combustion chamber.

Still another object of our invention is to provide a preheater of the class described where the heater proper is provided with a

passage for the admission and partial heating of the air, a separate passage for the admission of gases from the furnace, a mixing chamber for said air and gas and another passageway for the further heating of said mixture and still to have said heater of such construction that it may be formed in practice as a single strong casting well adapted to stand the extremes of temperature to which it is subjected.

The purpose of our invention is to provide a device of the character described, which is adapted to be applied broadly to heaters, furnaces, hot water heaters, heating boilers, stoves and any combinations of heaters broadly, and it will be understood especially that references in this description to the application of the device to an ordinary furnace door is meant as simply illustrative of one application of the device.

Further purposes and advantages of our invention will appear from the specifications and claims herein.

Fig. 1 is a top view of a fuel saver and smoke consumer embodying our invention.

Fig. 2 is a vertical central section of the mounting piece of the device applied to a furnace door and with the heater element proper shown in side elevation.

Fig. 3 is a horizontal sectional view through the heater member on line 3—3 of Fig. 2, so as to show the chambers of the upper level of said heater member.

Fig. 4 is a horizontal sectional view of said heater member on line 4—4 of Fig. 2 so as to show the chambers in the lower level in said heater member.

Figs. 5, 6 and 7 are vertical longitudinal sectional views of said heater member on lines 5—5, 6—6 and 7—7 respectively of Fig. 4.

As already suggested, our device in practice comprises two members, namely a support or mounting piece 10 and the heating member proper 11.

The support or mounting piece 10 consists of a hollow tubular part 12, preferably rectangular in cross-section and receiving at its inner end in sliding relation the shank or outer end 13 of the heater member 11. At its outer end the support 10 is provided with a plate 14 wider and higher than the tube 12, so as to cover all of the air admitting slots 15 in the furnace door 16. This plate is spaced a short distance from

the furnace door 16 by an outwardly extending flange on all edges of the plate 14, so as to form a shallow box upon the inner side of the furnace door to guide air from 5 all of the slots 15 to the cavity of the tube 12.

The support or mounting piece 10 is readily and securely fastened to the ordinary furnace door 16 by means of a bolt 18 extending 10 outwardly through a web conveniently formed in line with the plate 14 within the tube 12, the shank of which bolt extends outwardly through the most central air admitting slot 15 of the door 16 and is provided 15 with a nut 20 on its outer end. At the inner side of the nut is preferably placed a washer 21, which in turn bears against a clip 22 placed against the outer surface of the door 16. It will be understood that the clip 20 20 has a longitudinally extending slot 23 to allow of a considerable range of adjustment of the parts. Preferably there is formed an inwardly extending lug 24 adapted to rest against the material of the door at the bottom 25 of the slot 15 and so positively hold in proper upward position said clip 22 and therewith the mounting piece 10. It will be understood that the web 19 comes down only part way through the opening in the 30 tube 12 and not enough to reduce the air inlet through said mounting piece below desired capacity.

The heating member 12 consists of the substantially rectangular shank 13 adapted 35 to be slidingly mounted in and supported by the mounting piece 10 and the head 25 of general circular form at the inner end of said shank. In the main said heater member 11 is formed into chambers in what for convenience we have called the upper level and the lower level, the upper level being formed by the top 26 and the middle horizontal partition 27 and the lower level chambers being formed by said middle horizontal partition 27 and the bottom 28 of said heating member.

The lower level of said heater member 11 at its outer end is formed with a port 29, from which extends forwardly the air heating passage 30. The outer end 30^a of this 50 first air heating passage is funnel shaped in horizontal cross-section as appears from Fig. 4, said funnel shaped formation being made by the diagonal partition 30^b.

In the inner portion of its bottom portion 55 28 the head is provided with a port 31 for the admission of heated gases passing upwardly from the combustion chamber of the furnace. Extending from immediately above this port 31 is a rearwardly extending passageway 32 formed by the intermediate vertical walls 33 and 34 with the forward ends of said walls joined by a connecting wall 35. It will be understood that the bottom 60 of this passageway 32 is formed by the

bottom 28 of the heater member and that the top of said passageway is formed by the horizontal intermediate partition 27. The walls 33 and 35 and 34 are spaced away from the exterior wall of the heating member 70 forming respectively the forwardly extending air heating passage 30 already mentioned and the rearwardly extending air heating passage 36 on the other side of said heating member with a connection between the forward ends of said air passage 30 and 36 at the extreme forward end of the head. The outer end of the wall 34 does not reach to the diagonal partition 31, so that both the gas heating passageway 32 and the 75 rearward air heating passageway 36 lead into the mixing chamber 37.

This mixing chamber is, as it were, two stories high; that is it extends through both the lower level and the upper level of the device, by reason of the horizontal partition 27 being cut away for the extent of this mixing chamber, as will be seen by reference more particularly to Figs. 3, 4, 6 and 7. As the mixing chamber 37 passes into the upper 80 level it is enlarged from the triangular shape shown in Fig. 4 to occupy the whole width of the outer end of the upper level as shown more particularly in Figs. 3, 5, 6 and 7. 85 From the upper portion of this mixing chamber 37, the partially heated mixture of air and hot gases pass forward through passageways 38 and 39 on opposite sides of the shank portion of said heater member 90 into the large circular chamber 40 in the upper level of the head 25. From this chamber the port 41 leads from the inner side of said chamber and the inner end of said heater member out into the combustion chamber of the furnace. 95

The inner sides of the passageways 38 and 39 are formed by the side walls 42 and 43 respectively of a well 44 formed in the upper level of the shank 13 next to the head 25, said well being completed by its two end walls 45 and 46 respectively. The purpose of this well is to form a division between the forwardly extending mixture passages 38 and 39 and as a whole to form a baffle 100 to prevent the mixture of partly heated air and hot gases from passing out from the heater element too rapidly. 105

It will be noted that on the lower level the incoming air is subjected to the action of the heated walls of the long circuitous 110 passageways 30 and 36 with the inside walls 33, 34 and 35 further heated by the passage therethrough of the hot gases from the furnace. After the incoming air and hot 115 gases are mixed however, in the mixing chamber 37, said mixing chamber is enlarged and then ample space is provided for the forward passing of the mixture through the two forwardly extending 120 passageways 38 and 39. In the circular 125

chamber 40 in the upper level of the head, the mixture of hot gases and well heated air is further heated due to all the surrounding walls of this head being thoroughly heated 5 on account of being out in the combustion chamber of the furnace. Preferably the top of the head will slant downwardly as said head extends inwardly as shown particularly in Figs. 5, 6 and 7, so as to allow the 10 heat from the top to further heat the air therebeneath.

In practice when the heating member 11 is formed by casting, there is left an aperture 47 in the diagonal partition 31 in order 15 to clear the casting of the material used in the core. After the casting has been cleared, the aperture 47 is filled up with cement 47^a or other durable heat resisting material. With this slight exception, the whole heating 20 member proper 11 is formed as a single casting, exactly as it will be ultimately used. Being a single casting but with closely connected webs and walls, it is economical, of great strength and durability and particularly well adapted to absorb a great 25 amount of heat from the combustion chamber and pass the same on to the air passing through the various passageways of the heater member. The heater member being 30 all of one casting is free from any tendency to warp or have its partitions separate and leak as is the case in devices of this character formed out of a plurality of pieces of metal fastened together.

It will be seen that the heater member proper 11 may be readily adjusted to and held at the proper position relative to the combustion chamber including the fuel feed aperture by means of the shank portion 13 40 of said heater member being adjusted in the tubular part 12 of the supporting piece 10 and held in such desired position by the bolt 48.

Where a furnace is relatively small or 45 where other conditions of the furnace or its method of installation are such that under practically no circumstances will the full capacity of the air passing capacity of our fuel saving device be required, the amount 50 of fresh air admitted through the device may be readily and permanently reduced by reducing the cross area of the passage 30. This may be easily done by placing a partial filling 49 of cement or other material at the 55 outer end of the parallel portion of the passage 30, as shown particularly in Figs. 4 and 5.

It will be seen that the incoming current 60 of cold air passing on the bottom level of the heater device through the opposite ways 30 and 36 and the connection thereof at the extreme inner end of the head constantly tends to keep at a lower temperature the 65 whole device and particularly the lower part thereof, which is exposed to the greatest heat.

In other words, while the incoming air is being heated, it in turn tends to keep down the temperature of the heating member 11 and so prevents said member from being burned out or injuriously affected by the 70 high temperature to which it is subjected in the combustion chamber.

By experience and by actual use of our device, we have found that it eliminates the coal gas by consuming the same and thereby 75 more fully utilizes all the possible heat of the fuel. In most installations, the saving of fuel amounts to about thirty per cent, or produces a corresponding increase of heat 80 from a given amount of coal or wood fuel.

The use of this device in most boilers or other heating apparatus practically eliminates the escape of coal gas into the house or apartment.

Furthermore the device very greatly reduces the accumulation of soot in the heating apparatus and in the smoke pipe and similarly reduces the amount of escaping smoke. The fuel is burned so much more 85 efficiently that a saving is effected not only in the amount of fuel used but it appreciably reduces the labor of tending to the heater and removing the ashes. The coal is more thoroughly and evenly consumed 90 resulting in the elimination of sifting the ashes and reducing the amount of ashes to 95 be handled.

What we claim as new and desire to secure by Letters Patent is:—

1. In a fuel saver and smoke consumer the combination of a hollow tubular mounting having its outer end adapted to be secured to the inside of the furnace fuel door and a heater member having its outer end secured to the inner end of said mounting with its inner end adapted to project into the combustion chamber of the furnace, said heater member having near its inner end an opening 100 for the admission of hot gases and a passageway leading rearwardly therefrom an air inlet passage leading from the outer end of said heater member forwardly around said gas passageway and back nearly to the outer end of said heater member, a mixing 105 chamber at the junction of said gas and air passageways and a mixture passage leading inwardly and discharging into said combustion chamber through a port in the inner end of said heater member.

2. In a fuel saver and smoke consumer the combination of a hollow tubular mounting having its outer end enlarged to cover the door slits and adapted to be secured to the inside of the furnace fuel door and a heater member having its outer end secured to the inner end of said mounting with its inner end adapted to project into the combustion chamber of the furnace, said heater member having near its inner end an opening 115 for the admission of hot gases and a pas- 120

sageway leading rearwardly therefrom an air inlet passage leading from the outer end of said heater member forwardly around said gas passageway and back, nearly to the outer end of said heater member, a mixing chamber at the junction of said gas and air passageways and a mixture passage leading inwardly and discharging into said combustion chamber through a port in the inner 10 end of said heater member.

3. In a fuel saver and smoke consumer, the combination of a hollow tubular mounting having its outer end adapted to be secured to the inside of the furnace fuel door 15 and a heater member having its outer end slidingly secured to the inner end of said mounting with its inner end adapted to project into the combustion chamber of the furnace, said heater member having near its inner end an opening for the admission of hot gases and a passageway leading rearwardly therefrom an air inlet passage leading from the outer end of said heater member forwardly around said gas passageway 20 and back, nearly to the outer end of said heater member, a mixing chamber at the junction of said gas and air passageways and a mixture passage leading inwardly and

discharging into said combustion chamber through a port in the inner end of said heater member. 30

4. In a fuel saver and smoke consumer, the combination of a hollow tubular mounting having its outer end adapted to be secured to the inside of the furnace fuel door 35 and a heater member having its outer end secured to the inner end of said mounting with its inner end adapted to project into the combustion chamber of the furnace, said heater member having near its inner end an opening for the admission of hot gases and a passageway leading rearwardly therefrom on the lower level, an air inlet passage leading from the outer end of said heater member forwardly around said gas passageway 40 and back, nearly to the outer end of said heater member, a mixing chamber at the junction of said gas and air passageways and a mixture passage leading inwardly on the upper level and discharging into said 45 combustion chamber through a port in the inner end of said heater member. 50

In witness whereof we have affixed our signatures, this 2nd day of February, 1924.

IRVING S. BENJAMIN.
JOHN K. MARKWICK.
